UNITED STATES PATENT OFFICE

WILLIAM R. GRUBER, OF NEW YORK, N. Y.

PORTABLE ELECTRIC ARC LAMP

Application filed March 18, 1930. Serial No. 436,691.

This invention relates to electric arc lamps, and more particularly to lamps of a portable type adapted to dispense actinic rays of light upon photographic subjects, 5 the invention being an improvement over applicant's co-pending application for patent on "Photographic electric lamps," filed December 17, 1929, Serial Number 414,673.

It is well known that flash light powders, 10 for producing similar lighting effects, when detonated with accompanying explosions, serve to startle persons subjected to them, which are further annoyed by the fumes of the burning powder.

15 Incandescent electric lamps fail of success, because they lack brilliancy and power of illumination to the required extent.

Arc lamps, while possessing the desired attributes, have hitherto not met with favor 20 by commercial or amateur photographers because of their unwieldiness, lack of convenient control, and ready portability.

It is therefore an object of the present 25 invention to provide a portable electric lamp of the arc type, as readily carried and maneuvered as an ordinary flash light of commercial type, which it strongly resembles in shape and appearance.

30 A further feature is in the provision of an arc lamp, adapted to use an ordinary house current of 110 volts, and including a resistance coil arranged within the handle as a unit therewith.

35 These and other advantageous aims, as will later appear, are accomplished by the novel design, construction and combination of parts hereinafter described and illustrated in the accompanying drawings, forming 40 a material portion of this disclosure, and in which:—

Figure 1 is a longitudinal sectional view 45 of an arc lamp as made in accordance with the invention, the parts being in position for operation.

Figure 2 is a transverse sectional view taken on line 2—2 of Figure 1.

50 Figure 3 is a longitudinal sectional view of another embodiment of the invention having an exposed switch.

Figure 4 is a similar view of a further modified form of portable arc lamp.

In the preferred form, shown in Figures 1 and 2, a dielectric casing serving as a handle is designated by the numeral 10, the 55 same being provided at one end with a cap 11, and having secured at its opposite end a thin metallic cup 12, provided with ventilating apertures 13 in its side walls.

Hingedly attached to the upper edge of 60 the cap 12, by pivots 14, is a guard 15, provided at its lower edge with an indentation 16 to engage with a corresponding node 17 on the edge of the cup, whereby the guard is held erect when fully extended.

65 The interior of this guard is finished with a reflecting surface for a purpose further on evident.

Fastened rigidly in the casing 10 is a hollow plug 18, having an expanded upper portion extending outwardly within the cup 12, and provided with a helically grooved outer surface on its expanded portion.

70 At the upper end of the plug 18 is an in-reaching lug 19, and between it and the main portion of the plug is an opening to slidably receive and guide a rod 20, preferably of channel shaped cross-section, the inner end of the rod being slidable adjacently within the casing 10 to its lower end. The 75 outer end of the rod is turned at a right angle and fashioned into a socket 21, adapted to frictionally engage, in the manner of a clutch, with a carbon rod 22, held in axial alignment with a corresponding rod 23 set 80 in a clutch tube 24, disposed centrally within the plug 18 through which it passes, the lower end of the tube being flanged outwardly as at 25, to engage one of the terminals of a switch 26 held rigidly in the 85 casing 10, and through which projects its respective "on" and "off," transverse buttons 28 and 29.

90 Current enters the casing through conductors 30—31, passed through an opening 95 in the cap 11, the conductor 30 being connected with a binding screw 32, set in the base of the plug 18, the screw also engaging a conductor 33 leading to a resistance coil 34 wound upon the helix of the plug, the 99

other end of the coil being engaged by a conductor 35, leading to a mating binding screw 36 set in the plug and connecting with a spring contact 37 which engages the 5 bar 20 in whatever adjusted position the bar may be.

The conductor 31 leads to the switch 26, the other terminal of which is in electrical engagement with the base element 25 of 10 the clutch tube containing the lower carbon.

From the foregoing it may be seen that upon removing the carbons 22—23, the reflecting guard 15 may be turned upon the pivots 14 and disposed closely adjacent the 15 exterior of the cup 12, being foldable for that purpose.

It will also be noted that the perforations 13 serve to ventilate the interior of the cup, and permit the escape of heat from 20 the coil 34 when in operation.

In the modified form, shown in Figure 3, a similar casing 50 is provided with a cap 51 containing perforations 52, and having at its opposite end a hollow plug 53, provided on its outer side with a resistance coil 54, to which current is conveyed by a conductor 55 from a binding screw 56 set in the bottom of the plug, and connected with a conductor 57 leading from one terminal of a commercial "off" and "on" switch 58, disposed slightly beyond the cap 52.

One of the terminals of the switch 58 is directly connected with a clutch tube 59, in the upper end of which is set a carbon 60, a corresponding carbon 61 being held in a dielectric bushing 62 carried by a rod 63, slideable through an aperture in the outer end of the plug 53, into the casing 50 and to which current is connected by a spring 40 contact 64 engaged by a binding screw 65, with which is also connected a conductor 66 leading from the opposite end of the coil 54.

The outer central portion of the plug 53 is formed conically and of a larger diameter 45 than that receiving the coil 54, to act as a limit stop for a shell 67 slidably over the casing 50, and having a raised shield or guard portion 68, which engages and partially supports the dielectric bushing 62, finished on its inner convexed surface as a reflector.

In this type of lamp when the carbons 60—61 are removed, it will be obvious that the guard element 68 may be telescopically collapsed, thereby shortening the length of 55 the apparatus for carriage or storage.

In the device, illustrated in Figure 4, a similar casing 80 is provided at one end with a cap 81, through which passes a clutch tube 82, connecting with an "on" and "off" switch 83, as previously described, the other pole of the switch being connected with a conductor 84 leading to a binding screw 85 set in the base of a hollow dielectric plug 60 86, rigidly secured in the outer end of the

casing 80, and having on its outer surface a resistance coil 87, this coil being suitably connected by conductors with the binding screws 85 and 88, the latter of which also engages a contact 89 extending nearly to the outer end of the plug 86 and outturned at its end. 70

A cylindrical shell 90 is fixed on the outer end of the casing 80, and hingedly engaged to the outer rim of the shell, by pivots 91, is a guard 92 provided with an interior reflecting surface and fixed on its inner surface is a rod 93 spaced by a strip of insulation 94, these elements being held by insulated tubular rivets 95. 80

The lower end 96 of the rod 93 is curved to make spring contact with the angular end of the contact 89, while its upper end is turned angularly, as at 97, and provided with a socket 98 adapted to engage the upper carbon 99, a lower carbon 100 being held in the clutch tube 82. 85

An opening 101 is formed through the wall of the casing 80 to receive the lower rivet 95 when the guard 92 is turned over 90 in the manner first described, and it will be obvious that the guard 92 may be turned on the pivots 91 when the carbons are removed to fit closely against the casing 80. 95

Although I have described my improvements with considerable detail and with respect to certain particular forms of my invention, I do not desire to be limited to such details since many changes and modifications may well be made without departing from the spirit and scope of my invention in its broadest aspect. 100

Having thus described the invention, what is claimed as new and desired to secure by Letters Patent, is:— 105

1. An arc lamp comprising a dielectric casing, a carbon mounted axially therein, a second carbon, means for holding said second carbon in register with the first carbon said means being foldable alongside said casing, and means for controlling current to said carbons. 110

2. An arc lamp comprising a dielectric casing adapted for hand manipulation, an electric circuit in said casing, a pair of carbon electrodes, one of said electrodes being directly connected in the circuit, a reflecting guard for the other electrode, and means to collapse said guard relative to said casing upon the removal of said electrodes. 115

3. An arc lamp comprising a dielectric casing, a carbon clutch tube fixed therein, a carbon held in said tube, a rod slideable lengthwise said casing against the wall thereof and extending outwardly, a socket on the extending end of said rod, a carbon therein, a coil surrounding a part of said casing, said coil having one terminal connected in an electric circuit and the other terminal with said rod, a perforate guard 120

enveloping said coil, and a second carbon alined with the first carbon and in engagement with said circuit.

4. An arc lamp comprising a dielectric casing adapted for hand manipulation, an electric circuit in said casing, a pair of carbon electrodes, one of said electrodes being directly connected with one of the terminals of said circuit, an insulated support for the other electrode, said support being at all times in circuit, a reflecting guard for said support, said guard being collapsible with respect to said casing upon removal of said electrodes, and operative connections between said guard and support.

5. A portable arc lamp comprising a non-conducting casing having a circuit connected therewith, a clutch tube connected with one of the terminals of said circuit, a carbon in said tube, a second carbon movable in axial relation thereto, an insulated support for said second carbon, said support being in circuit with the first carbon, a reflector guard for the second carbon, and means to retain said guard in either of two positions.

6. A portable arc lamp comprising a non-conducting casing having a circuit connected therewith, a pair of carbons respectively inner and outer, said inner carbon being directly connected to one terminal of said circuit and the outer carbon to the other terminal therefor, a support for the outer carbon, said support being collapsible with respect to the casing, a reflector combined with said support, and means for retaining said support in either of its adjusted positions.

7. A portable electric arc lamp comprising a cylindrical dielectric casing closed at one end, a hollow dielectric plug fixed in the other end, a cup surrounding said plug, said plug having a coil wound thereon, binding screws fixed in said plug connected with the terminals of said coil, a carbon electrode in electrical engagement with one terminal of said coil, a support slidable in said plug and casing in electrical engagement with one of said carbons, and a reflecting guard for said support and electrode carried thereby, said guard being collapsible with respect to said casing upon the removal of said electrodes.

8. A portable electric arc lamp comprising a cylindrical dielectric casing closed at one end, a hollow dielectric plug fixed in the other end, a cup surrounding said plug, binding screws fixed in said plug connected with the terminals of an electric circuit, a carbon electrode in electrical engagement with one terminal of said circuit, a support slidale in said plug and casing in electrical engagement with one of said screws, and a second carbon electrode carried by said support.

9. A portable electric arc lamp compris-

ing a cylindrical dielectric casing closed at one end, a metal cup fixed on the other end, said cup being expanded in diameter and having perforate side walls, a hollow dielectric plug fixed in said casing to extend outwardly into said cup, a carbon clutch tube fixedly extending axially thru the base of said plug to move closely adjacent the inner surface of said casing, a carbon carrying socket on the inreaching outer end of said rod, a second carbon in said socket registering with the first named carbon, a guard for said rod, said guard having a reflecting semi-cylindrical inner surface, said guard being hingedly connected to the outer end of said cup to extend outwardly therefrom and to fold over said cup, means to retain said guard when extended, and a pair of binding screws in the base of said plug.

In testimony whereof I affix my signature.

WILLIAM R. GRUBER.
